STOP CLOCK

Basil Lavitol, 27 Upland Way, Cedar Grove, N.J.

Filed June 6, 1963, Ser. No. 75,248

Term of patent 14 years

(Cl. D42—1)

FIG. 1

FIG. 2

FIG. 3

FIGURE 1 is a front elevational view of a stop clock showing my new design.

FIGURE 2 is a right-side elevational view thereof; and

FIGURE 3 is a rear elevational view thereof.

The essential features of my design are shown in full lines and reside in the combination of a nine-sided clockface and a single hand which extends outward of the extreme periphery of the clockface which is defined by the moulded border, all as shown.

I claim:

The ornamental design for a stop clock, substantially as shown and described.
